[57] ABSTRACT

The concentration of impurities in wet-process phosphoric acid limits the usefulness of the acid for the production of fertilizers, feed-grade phosphate and detergents. The aluminum, magnesium, and fluoride impurities are removed with the calcium sulfate hemihydrate filter cake by hydrolyzing and recycling the off-gas scrubber solutions in the presence of a ferric iron catalyst. The aluminum and magnesium are reduced to less than 0.1 percent in the acid product by the precipitation

of $(\text{Ca},\text{Mg})\text{Al}_2\text{F}_8 \cdot 2\text{H}_2\text{O}$, which is acid insoluble and suitable for storage with the byproduct calcium sulfate. Ferric iron also serves as a catalyst for the simultaneous precipitation of $(\text{Na},\text{K})_2\text{SiF}_6$. Subsequent additions of potassium as, for example, in the teachings of Gilbert (U.S. Pat. No. 3,338,675), can then be applied to obtain a purified phosphoric acid product suitable for most commercial applications. The added potassium serves two purposes in the 40 to 55 percent P_2O_5 acid since ferric iron is reduced to 0.25 percent Fe_2O_3 by the precipitation of $\text{Fe}_3\text{KH}_{14}(\text{PO}_4)_8 \cdot 4\text{H}_2\text{O}$ and the SiF_6^{2-} is reduced to about 0.2 percent by the precipitation of K_2SiF_6 . This subsequent precipitate contains about 50 percent P_2O_5 and is as effective as superphosphate $[\text{Ca}(\text{H}_2\text{PO}_4)_2 \cdot \text{H}_2\text{O}]$ in supporting plant growth.
